UNITED STATES PATENT OFFICE

95,581

DESIGN FOR TEXTILE FABRIC

Curt Erwin Forstmann, Montclair, N. J.

Application January 2, 1935, Serial No. 54,685

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for Textile Fabric, as shown in the following specification, reference being had to the accompanying drawing, forming part thereof.

In the drawing, the sole figure of which is a plan view of a piece of the textile fabric embodying the design of the present invention, the cloth depicted is of a single color.

The design pattern comprises parallel series

of oblique angled parallelograms arranged in herringbone formation, adjacent series interlocking so that the pattern covers the entire area leaving no intervening spaces. The boundaries of the parallelograms are defined by rows of stitches, the individual stitches being all substantially parallel and extending in the direction of the series and therefore obliquely with respect to the sides of the parallelograms.

I claim:

The ornamental design for textile fabric as shown and described.

CURT ERWIN FORSTMANN.
